UNITED STATES PATENT OFFICE.

HENRY KETTEN, OF PARIS, FRANCE, ASSIGNOR TO CHICKERING & SONS,
OF BOSTON, MASSACHUSETTS.

PIANO-FORTE ACTION.

SPECIFICATION forming part of Letters Patent No. 224,091, dated February 3, 1880.

Application filed December 13, 1879.

To all whom it may concern:

Be it known that I, HENRY KETTEN, of Paris, France, have invented a new and useful Improvement in Piano-Forte Actions; and 5 I do hereby declare the same to be described in the following specification and represented in the accompanying drawing, which denotes a side elevation of a grand-piano-forte hammer and the operative mechanism thereof as provided with my invention, the nature of which 10 is duly set forth in the claims hereinafter made.

The object of my improvement is to enable what is termed "rapid repeating" of the hammer to be accomplished with certainty and 15 ease, and to cause the hammer in repeating not only to always rebound from the spring, but to be held up to the necessary extent with respect to, or prevent it from dropping too far 20 from the spring preparatory to each depression of the key.

Without the auxiliary springs hereinafter mentioned there is, in a rapid repeating, a liability of the hammer to either not properly fall 25 from the string, or to rebound too far, or not to be held up sufficiently for the key or its jack to properly actuate it, (the said hammer.)

In carrying out my invention I employ with the hammer A and the under hammer or elevator, B, auxiliary springs, one of which is 30 shown at a and the other at b in the drawing. The first spring—viz., that marked a—is fastened to the block c, to which the hammer A is hinged, and it projects over the tail-block d 35 of the hammer in manner as represented. The other spring, which, in this instance, is a helical one, is arranged directly underneath the under hammer or elevator, B, and is supported on a shelf or bar, C.

40 The main operative spring of the under hammer, B, and jack D is shown at E, it being connected to them by loops c d', and pivoted at its vertex to a projection, e, extending down from the bar C.

The key is shown at F and the back catch 45 of the hammer at G. On the key being depressed so as to cause the hammer A to be thrown up by the under hammer acted on by the jack, such hammer A, just before it meets the string, will be forced in contact with the auxiliary spring a. In falling the hammer departs from the spring a. While the helical spring b aids in holding the under hammer up, it eases its fall upon the head of the jack and co-operates to advantage with the spring a 55 while the repeating is being performed.

In practice it is found that with my improved action there is great ease in playing, and that very rapid repeating can be accomplished without any danger, comparatively 60 speaking, of the main hammer not properly dropping from the string or the under hammer or elevator not being held up after passage of the jack out of the notch of the said elevator.

65 What, therefore, I claim as my invention is as follows:

1. The piano-action consisting of the key F, hammer A, under hammer or elevator, B, jack D, and spring E, arranged and applied as represented, in combination with the auxiliary spring b, adapted to the said elevator and supported and arranged substantially as set forth.

2. The piano-action consisting of the key F, 75 hammer A, under hammer or elevator, B, jack D, and spring E, arranged and applied as represented, in combination with the auxiliary springs a and b, adapted to operate with the hammer and the elevator substantially as set 80 forth.

HENRY KETTEN.
